HOOD ORNAMENT FOR AUTOMOBILES

Joan Hanscom, Providence, R. I.

Application April 7, 1951, Serial No. 14,750

Term of patent 14 years

(Cl. D14—18)

To all whom it may concern:

Be it known that I, Joan Hanscom, a citizen of the United States, residing at Providence, Rhode Island, have invented a new, original, and ornamental Design for a Hood Ornament for Automobiles, of which the following is a specification, reference being had to the accompanying drawing, forming a part hereof.

Figure 1 is a perspective view of a hood ornament for automobiles, showing my new design.

Figure 2 is a front elevational view of my new hood ornament.

Figure 3 is a rear elevational view thereof; and Figure 4 is a side elevational view.

I claim:

The ornamental design for a hood ornament for automobiles, as shown.

JOAN HANSCOM.
